UNITED STATES PATENT OFFICE.

KÁLMÁN HAJDÚ, OF YOUNGSTOWN, OHIO.

COMBINED RAZOR AND SCISSORS.

Specification of Letters Patent.

Patented Jan. 2, 1912.

1,013,159.

Application filed June 23, 1911. Serial No. 634,901.

To all whom it may concern:

Be it known that I, KÁLMÁN HAJDÚ, a subject of the King of Hungary, residing at Youngstown, in the county of Mahoning and State of Ohio, have invented certain new and useful Improvements in a Combined Razor and Scissors, of which the following is a specification, reference being had thereto in the accompanying drawing.

10 This invention relates to a combined razor and scissors, and the primary object of the invention is to furnish a scissor blade with a recess adapted to receive a razor blade, and by disconnecting the scissor blades, the 15 blade equipped with the razor blade can be used for shaving.

Another object of this invention is to construct one of the blades of a pair of scissors or shears whereby it can be equipped with a 20 razor blade and used similar to an ordinary safety razor, the provision made for the razor blade not impairing the usefulness of the scissors or shears.

With the above and other objects in view 25 as may hereinafter appear, the invention resides in the novel construction, combination and arrangement of parts to be herein-after specifically described and then claimed.

Reference will now be had to the drawing,

30 wherein:—

Figure 1 is an elevation of a pair of scissors or shears in accordance with this invention, Fig. 2 is a similar view of a detached blade, Fig. 3 is an enlarged cross sectional view of the scissor blade provided with a 35 razor blade, and Fig. 4 is an enlarged perspective view of a detached scissor blade showing the provision made for the razor blade.

40 The reference numerals 1 and 2 denote scissor blades having handles 3, said blades being pivotally and detachably connected together by a screw 4 in the ordinary and well known manner, the blades being detached when it is desired to sharpen the same.

45 My invention resides in the construction of the blade 2 and the provision made for a razor blade. The inner side of the blade 2

is provided with an oblong recess 5 and the 50 upper edge of the wall 6 of said recess is provided with a series of transverse slots 7 forming teeth or prongs 8, which constitute the safety feature of the razor, these teeth preventing the cutting edge of the razor 55 blade from entering the flesh. As the outer edge or that edge of the blade 2 opposite the cutting edge thereof, is beveled, the teeth 8 will be beveled and assist to a certain degree in determining the proper angle to 60 hold the blade 2 when shaving.

Detachably mounted in the recess 5 is the flat holder 9 of a blade 10, said holder and blade having a transverse opening 11 adapted to register with an opening 12 in the wall 65 6 of the recess, said openings receiving a screw 13 adapted to retain the razor blade within the recess 5.

To assist the screw 13 in retaining the 70 razor blade within the recess 5 and to provide a firm seat for said blade, the ends of the recess terminate at a point slightly removed from the edge 14 of the blade 2, thereby forming lips 15 that engage the cutting edge of the blade 10, at the ends thereof, thereby preventing the blade 10 from shifting within the recess, when the razor is in use. In removing the cutting edge of the blade 10 from the edge 14 of the blade 2, the cutting edge of the blade 10 will register 75 with the upper edges of the teeth 8, and in making a wide stroke when shaving, the edge 14 of the blade 2 will co-operate with the teeth 8 in preventing the razor edge from entering the flesh.

80 Since the razor blade is detachable, it can be easily removed and sharpened, and when the scissors are in use, it is preferable to leave the razor blade off of the scissor blade and thereby avoid all danger of the edge 85 of the razor blade being injured or injuring the operator of the scissors.

85 What I claim is:—

90 A pair of scissors comprising a pair of blades, each having a cutting edge, said cutting edges co-acting with each other, bevelled teeth formed along the opposite edge 95 of one of said blades, that blade having the

teeth being further provided in one face with a recess extending to the free ends of the teeth, the back wall of said recess having an opening which extends through the 5 blade, a razor blade mounted in said recess, and means extending through the razor blade and into said opening for securing the razor blade in position.

In testimony whereof I affix my signature in the presence of two witnesses.

KÁLMÁN HAJDÚ.
